UNITED STATES PATENT OFFICE.

JAMES G. COLLINS, OF KALAMAZOO, MICHIGAN, ASSIGNOR TO ATLAS PRESS COMPANY,
OF KALAMAZOO, MICHIGAN.

MANDREL AND STRAIGHTENING PRESS.

Application filed November 6, 1919. Serial No. 336,021.

To all whom it may concern:

Be it known that I, JAMES G. COLLINS, a citizen of the United States, residing at the city and county of Kalamazoo, State of Michigan, have invented certain new and useful Improvements in Mandrels and Straightening Presses, of which the following is a specification.

This invention relates to a combined mandrel and straightening press.

The main objects of this invention are to provide a combined mandrel and straightening press which is compact in structure, very convenient to use and at the same time simple and economical to produce.

Further objects, and objects relating to structural details, will definitely appear from the detailed description to follow.

I accomplish the objects of my invention by the devices and means described in the following specification. The invention is clearly defined and pointed out in the claim.

A structure which is a preferred embodiment of my invention is clearly illustrated in the accompanying drawing forming a part of this specification, in which:

Fig. I is a front elevation of my combined mandrel and straightening press, the operating lever being broken away.

Fig. II is a side elevation looking from the right of Fig. I.

Fig. III is a detail vertical section on a line corresponding to line 3—3 of Fig. I.

Fig. IV is an enlarged detail section on a line corresponding to line 4—4 of Figs. I and II.

In the drawing similar reference characters refer to similar parts throughout the several views, and the sectional views are taken looking in the direction of the little arrows at the ends of the section lines.

Referring to the drawing, the base 1 is provided at its rear end with a standard or upright 2 having a forward projection or overhang 3 at its upper end, overhanging the work table 4. The ram 5 is mounted on the overhang. The ram is actuated by a lever mechanism designated generally by the numeral 6, the mechanism illustrated being

that shown in the patent to Eames No. 50 1,038,543, dated September 17, 1912. As the details of the operating mechanism form no part of my present invention, I do not further illustrate the same herein.

The table is provided with an adjustable 55 work holder 7. At each side of the work holder 7 the table is provided with lateral projections 8, the projections having aligned grooves 9 therein adapted to receive the work supporting blocks 10. These grooves 60 9 are in the plane of the ram, that is, they are aligned therewith as shown in the drawings. The grooves have beveled sides 11 and channels 12 at the bottom, the sides being inclined so that any chip of metal or 65 the like which may fall thereon will slide into the channel and not interfere with the blocks. At the rear of the ram the table is provided with a horizontally disposed supporting bar 13 having arms 14 adjustable 70 thereon, the arms being provided with centering pivots 15 and 16 so that a shaft or other part to be straightened may be centered on these pivots and turned and marked to indicate the bends or distortions thereof, 75 and then placed upon the blocks 10 and the ram actuated to straighten the same.

My improved press enables the accomplishment of a large amount of work, that is, the work may be gauged and the distortion 80 indicated thereon and directly laid upon the straightening blocks. The machine is also adapted for general use as a mandrel or arbor press, the parts being arranged so as not to interfere in such use. It has the further advantage of being simple and economical to produce.

I have illustrated and described my improvements in an embodiment which I find very satisfactory. I have not attempted to 90 illustrate or describe certain modifications or adaptations as I believe the disclosure made will enable those skilled in the art to which my invention relates to embody or adapt the same as may be required.

Having thus described my invention, what I claim as new and desire to secure by Letters Patent is:

In a structure of the class described, the combination of a base, a standard, a ram and actuating means therefor, a work table having lateral projections at its sides, such 5 projections having aligned grooves therein in the plane of the ram, work supporting blocks adjustable in said grooves, a supporting bar disposed horizontally through the table at the rear of said ram, and arms pro-

vided with centering pivots adjustably 10 mounted on said supporting bar.

In witness whereof, I have hereunto set my hand and seal in the presence of two witnesses.

JAMES G. COLLINS. [L.S.]
